COOKING UTENSIL COVER

Peter Muller-Munk, Pittsburgh, Pa., assignor to Ekco Products Company, Chicago, Ill., a corporation of Illinois

Application April 20, 1948, Serial No. 145,852

Term of patent 7 years

(Cl. D44—15)

To all whom it may concern:

Be it known that I, Peter Muller-Munk, a citizen of the United States, residing at Pittsburgh, county of Allegheny, State of Pennsylvania, have invented a new, original, and ornamental Design for a Cooking Utensil Cover, of which the following is a specification, reference being had to the accompanying drawing, forming part thereof.

Fig. 1 is a top plan view of a cooking utensil cover, showing my new design.

Fig. 2 is a side elevational view.

Fig. 3 is a side elevational view when viewed from the right of Fig. 2.

Fig. 4 is a vertical sectional view taken on line 4—4 of Fig. 2.

The dominant feature of the design resides in the knob on the cover as shown.

I claim:

The ornamental design for a cooking utensil cover, as shown and described.

PETER MULLER-MUNK.
